UNITED STATES PATENT OFFICE.

CHARLES E. MCGILL, OF COLORADO SPRINGS, COLORADO.

CONFIDENTIAL SHEET. VD.

1,257,506.

Specification of Letters Patent. Patented Feb. 26, 1918.

Application filed September 21, 1916. Serial No. 121,466.

To all whom it may concern:

Be it known that I, CHARLES E. MCGILL, a citizen of the United States, residing at Colorado Springs, in the county of El Paso, 5 State of Colorado, have invented certain new and useful Improvements in Confidential Sheet-Blinds; and I do hereby declare the following to be a full, clear, and exact description of the invention, such as will enable others skilled in the art to which it 10 pertains to make and use the same.

This invention relates to a confidential sheet-blind, or shield attachment for typewriters.

15 The purpose of the invention is to enable a typist to safely write private or confidential matter, notes or dictation on the typewriter in the presence of others, bystanders and onlookers, without them seeing what the 20 typist is writing; while at the same time the typist himself sees sufficient of what is being written to do the work properly, that is the typist sees one or two lines of writing.

25 The essence of the invention is the use of a sheet of paper identical with the one upon which the writing is being performed, or similarly pliant and opaque sheet as long and as wide as the one being written on, held in a proper position and covering substantially all of that portion of the sheet being written on whereon characters have been impressed.

30 A further object of the invention is to provide a device of this character which is exceedingly simple in construction and can be readily applied to a well known make of typewriter so that when in place thereon a sheet of suitable paper or flexible material can be supported over, in advance of, and 35 to the rear of, the platen so as to conceal not only the lines of typewritten matter immediately above the scale bar adjacent the platen, but all the printed matter on the page as it emerges from the typewriter until 40 the page is removed from the machine.

45 A still further object of the invention is to provide a device of this character so constructed that when the shield is in use it will in no way interfere with the operation of the necessary parts of the machine.

50 It is a well known fact that in many instances it is desired to typewrite matter

which is strictly confidential, but if the typewritten matter is exposed to the scrutiny of a person other than the operator they can 55 upon glancing at the typewritten sheet comprehend the gist of the matter being written.

With the above and other objects in view, as will be hereinafter apparent, the invention consists in general of certain novel details of construction and combinations of parts hereinafter fully described, illustrated in the accompanying drawings, and specifically claimed.

In the accompanying drawing, like characters of reference indicate like parts in the several views, and:

Figure 1 is a fragmentary front elevation of a typewriter equipped with the device.

Fig. 2 is a top plan view of the same.

Fig. 3 is a detail perspective view of one of the paper guides.

Fig. 4 is a detail perspective view of the envelop holder.

Fig. 5 is a diagrammatic view showing the relative positions of the platen roll, platen back, sheet being written on and blind-sheet.

Referring to the drawing 1 indicates the platen of the typewriter which is here indicated as being of the well known "Underwood" type although it is obvious that the invention is not intended to be confined to any particular make or type of typewriter. Slidably associated with the platen in the usual manner are the paper guides 2, said guides being of the conventional form and having attached thereto in any suitable manner sockets 3 in which are fixed the inner ends of the spring fingers 4, said fingers being curved upwardly and having their inner ends turned upwardly as at 5 so that the shield 6 can have its side edges readily engaged under the fingers and since the fingers engage yieldably the upper edges of the bars 7 of the guides 2 it is obvious that the shield will be held firmly in place, but can be readily removed when desired.

The confidential sheet-blind or shield preferably is a sheet of paper identical with the one being written on, or it can be formed from any other similarly flexible, pliant, opaque sheet of material, and can be of any color desired; but it is preferable that it be of

the same color as the sheet being printed upon, since it will then be less noticeable to an observer.

The envelop holding arm 8 consists of a block 9 which is pivotally connected to the frame of the typewriter, said block being provided with the shoulder 10 which has engaged therewith the bar 11 of the spring finger 12, said bar being held in clamped engagement with the shoulder by the adjacent end of the arm 8. The spring finger 12 is curved downwardly and has its free end turned upwardly as at 13 so that the front edge of the shield 6 can be readily slipped under the finger 12 and will be held yieldably engaged with the upper edge of the arm 8. To prevent accidental slipping of the shield the arm 8 has its upper edge provided with serrations 14 which lie directly under the point where the finger 12 exerts the most pressure.

Thus it will be seen that the confidential sheet-blind or shield 6 can be readily positioned with its side edges engaged between spring fingers 4, and bars 7, or otherwise; or, its front edge engaged centrally between the arm 8 and spring finger 12, or otherwise.

The shield will be held in such a position that its rear surface will cover the sheet after the writing is accomplished but will permit said sheet to be readily removed from the platen or engaged therewith.

In operation a sheet of paper on which private or confidential matter, notes or dictation is to be written is placed in the typewriter. The blind sheet, that is, a plain sheet of paper similar to the one to be written upon, or a similarly pliant, opaque sheet, is now drawn across the top of the typewriter from the back toward the front of the machine, covering the sheet to be written upon. The front edge of the blind sheet is caught under the tongue on the envelop holder (Underwood machine), or it may be held by fastenings at the sides, or otherwise, if preferred. The sheet is then pulled forward till only one or at most two lines of writing on the writing sheet will be visible to the operator, who is then ready to go ahead with his private or confidential work.

The blind sheet is fixed, stationary. The writing sheet, that is the one on which the operator is writing, moves just as usual; but, it now moves under the blind sheet, and the work is shielded, the writing sheet showing only a line of writing.

Thus is the typist's work protected from the scrutiny of others.

Having thus described, the invention, what is claimed as new, is:—

1. The combination with a typewriting

machine, of holding means carried thereby and a blind sheet held in the holding means in position to cover the longitudinal extension of the sheet that has passed beyond the line of writing in the machine, the blind sheet being of a material of such flexibility as to insure gravitation thereof beyond the holding means into conformity with the corresponding portion of the sheet written upon.

2. The combination with a typewriting machine, of holding means carried thereby and a blind sheet held in the holding means in position to cover the longitudinal extension of the sheet that has passed beyond the line of writing in the machine, the blind sheet being of a material of such flexibility as to permit of forward swinging of the portion beyond the holding means to disclose the corresponding part of the sheet written upon.

3. The combination with a typewriting machine, of holding means carried thereby and a blind sheet removably held in the holding means in position to cover the longitudinal extension of the sheet that has passed beyond the line of writing in the machine, the blind sheet being of a material of such flexibility as to insure gravitation thereof beyond the holding means into conformity with the corresponding portion of the sheet written upon.

4. The combination with a typewriting machine, of holding means carried thereby and a blind sheet removably held in the holding means in position to cover the longitudinal extension of the sheet that has passed beyond the line of writing in the machine, the blind sheet being of a material of such flexibility as to permit of forward swinging of the portion beyond the holding means to disclose the corresponding part of the sheet written upon.

5. In a typewriting machine, the combination with a carriage including a platen, of paper guides adjacent to the platen, a blind sheet and means carried by the paper guides for yieldably engaging the sheet to hold the same in position to cover a sheet being written upon, as and for the purpose set forth.

6. In a typewriting machine, the combination with a carriage including a platen, of an envelop arm, a resilient finger carried thereby, and a shield of flexible material yieldably engaged by the finger of the envelop arm and held in position to cover a sheet being printed upon, as and for the purpose set forth.

7. In a typewriting machine, the combination with a carriage including a platen, of paper guides associated with the platen, resilient fingers supported by the guides, an

envelop arm, a resilient finger carried by the arm, a shield of flexible material yieldably engaged by the fingers of the paper guides and envelop arm, and held in position to cover a sheet being printed upon, as and for the purpose set forth.

In testimony whereof, I affix my signature, in the presence of two witnesses.

CHARLES E. MCGILL
